HERMENEGILDE CARRIER, OF AMESBURY, MASSACHUSETTS, ASSIGNOR TO G. W. J. MURPHY COMPANY, OF AMESBURY, MASSACHUSETTS, A CORPORATION OF MASSACHUSETTS.

DOOR LATCH.

Application filed July 24, 1924. Serial No. 727,899.

This invention relates to door latches and in particular to a type of latch finding a special application to the doors of automotive vehicles of the closed type, having provision whereby it may conveniently be locked from the inside against operation from the exterior and wherein it will not be necessary separately to manipulate the locking mechanism when opening the door from the inside. In the accompanying drawings I have shown by way of example an illustrative embodiment of my invention incorporated in a door latch embodying various features of construction disclosed and claimed in my copending applications Serial Nos. 681,770 and 704,143. In these drawings:—

Fig. 1 is an elevation of the latch as seen from the inner side;

Fig. 2 is a section on the line 2—2 of Fig. 1;

Fig. 3 is a section on the line 3—3 of Fig. 1 on an enlarged scale; and

Fig. 4 is a section on the line 4—4 of Fig. 1.

Referring particularly to Figs. 1 and 2 of the drawings, the latching mechanism herein shown is organized on a casing of generally angular form including a plate 17 adapted to be placed flush with the inner face of the door, being mortised into the lock rail and a flange 19 adapted to be set flush with the edge of the door. From the flange 19 projects outwardly a hollow housing 21 which accommodates, as best shown in Fig. 2, a latch bolt 23 which may be pivoted on a substantially horizontal axis formed by a pin 25 journaled in the outer wall of the housing and in an inner wall formed by the plate 27 fixed in the inner surface of the flange 19. The end of the bolt is projected by the spring 29 through a suitable opening in the bottom of the housing to engage a keeper on the door jamb and the upper portion of the housing 21 may serve as a stop for the bolt.

To swing the bolt against the force of the spring 29 to retract it within the housing and permit the door to be opened, there may be provided on the pivot 25 an arm 31 located inwardly of the plate 27, lying flat against the same and extending toward the angle defined between the plate 17 and the flange 19. The arm 31 may be operated to swing the bolt by means of a movable bar or

lever 35 lying against the inner face of the plate 17 and having an end engaging the end of the arm 31 adjacent the junction of this plate with the flange 19. Herein the lever 35 is pivoted on the plate 17 and on the auxiliary plate 37 secured thereto which forms a partial housing for this lever and other mechanism to be described. If the lever 35 is swung clockwise, viewing Fig. 1, the end of arm 31, viewing Fig. 2, will be depressed and the latch bolt 23 will be retracted within the housing 21 against the force of spring 29.

The lever 35 may be operated from the exterior of the door by means of a rotatable handle of conventional type having a square spindle 41 engaging a cam 43 journaled in the plates 17 and 37 and coplanar with the lever 35. It will be apparent from Fig. 1 that if the cam is rocked counterclockwise from the position shown in that figure, the right hand end of the lever 35 will be depressed to unlatch the bolt. Preferably the arrangement is such that the bolt will be lifted in whichever direction the spindle 41 is turned and for this purpose I may provide an arm 45 presented at the opposite side of the cam 43 and connected to the opposite end of the lever 35, the arm 45 being herein formed as an extension of a fork 47 pivoted to the left hand end of the lever 35 (forming a portion of another operating mechanism hereinafter to be described) and constrained to move in a substantially vertical direction by the threaded rod 49 screwed into the fork 47 and guided in the lug 51 carried by plate 17. It will be apparent that if the cam 43 is rotated in a clockwise direction from the position shown in Fig. 1, it will lift the arm 45 and depress the right hand end of lever 35 to raise the bolt 23.

To operate the latch from the inner surface of the door there is herein shown a pull rod moving substantially vertically adjacent the plate 17 and comprising the fork 47 into which taps the screw 49 already referred to, the whole being guided in the lug 51 and normally depressed by the helical spring 53 surrounding screw 49 and interposed between the fork 47 and the lug 51. The rod 49 may be raised against the spring 53 by any suitable means but I have herein shown a lever 59 secured thereto and mounted (see Fig. 4) on a spindle 61 pro-

jecting through the plate 17 to the exterior of the door and having a frusto-conical extension 63 on which may be clamped a lever handle 65 by means of nut 67.

- 6 It will be apparent that control of the bolt 23 from the outside by the spindle 41 may be prevented by holding the cam 43 against movement and for this purpose I have herein provided a suitable dog or 10 tent in the form of a plunger 69 extending through plate 17 from the inside of the door and adapted to move in guiding sleeve 71 carried by the plate 17 under the control of a cap 73 secured to the outer end of the 15 plunger 69 and having a flange or skirt embracing the outer end of the sleeve 71. In Fig. 3 the dog 69 is shown in protracted or locking position in which it is retained by the engagement of a spring pressed ball 75 20 carried thereby with a recess 77 in the sleeve 71. The dog 69 may be withdrawn so that its end is at least flush with the interior surface of plate 17 and out of the path of cam 43, the cap 73 moving to the dotted line 25 position in Fig. 3 and may be retained in this position by the engagement of the ball 75 with a second recess 79 in the sleeve.

The plunger 69 moves in a direction substantially parallel to the axis of the cam 43, 30 as best seen from Fig. 1, and this construction, among other advantages, facilitates locking the cam 43 against movement in either direction as is necessary in the construction shown wherein the cam 43 if 35 turned in either direction would lift the bolt. To lock the cam the plunger 69 may be provided with a square end engaging the abrupt shoulders of a notch 81 in the end of the cam. Thus with the cam in its normal 40 neutral position to which it is returned under the action of the springs 29 and 53 as shown in Fig. 41, the cap 73 at the interior of the door may be depressed in the manner of a push button shifting the plunger 45 69 to the full line position shown in Fig. 3 and the end of the plunger 69 will enter the recess 81 in the end of the cam and effectively lock it against turning in either direction.

- 50 The door is thus locked against opening by manipulation of the handle on the outside. It could, of course, be released by withdrawing the spindle by manipulation of the cap 73 but the construction herein 55 shown provides for automatically disengaging the dog 69 from the cam 43 when the inner handle 65 is manipulated. For this purpose a suitable member set in motion by the handle 65 and conveniently connected 60 to one of the parts of the lock operated by this handle may be utilized to displace member 69 from the full line position of Fig. 3. Herein this displacing element takes the form of a strip 83 mounted on the member 65 45 and overlying the inner end of dog 69

and having its end portion 85 bent inwardly toward the plate 17, as best shown in Fig. 3, to present a diagonal camming surface to the end of movable plunger 69. It will be apparent from Figs. 1 and 3 that if the 70 dog 69 is in the projected full line position shown and the handle 65 is manipulated, to operate the pull rod and therewith to raise the member 45 the member 83 will be drawn upwardly from the position shown in Fig. 3 75 and the inner diagonal surface of the extension 85 will wipe across the end of the plunger 69 and move it to the right, viewing Fig. 3. In this action the ball 75 yields and toward the conclusion of the camming 80 movement caused by the surface 85, it will be presented in part at least to the right hand recess 79. As the ball 75 tends to enter this recess under the action of the spring the curved surface of the ball will itself act 85 in the manner of a cam completing the movement of the plunger dog 69 to the right as the ball snaps into position with the end of the dog out of the path of cam 43.

It will thus be seen that operation of the 90 inner handle always releases the cam 43 and that thereafter the bolt 23 may be lifted either from the inside or the outside until intentionally locked again from the inside by the depression of the cap 73.

A finish may be provided at the interior 95 of the mechanism by the use of a sleeve 87 having a barrel which fits sleeve 71, covers recess 79 and is embraced by cap 73 and an annular flange 89 adapted to rest on the 100 inner surface of the door. Herein flange 89 is somewhat spaced from plate 17 to accommodate the usual upholstery.

I have described in considerable detail the 105 particular mechanical construction shown in the accompanying drawings as an example of the invention in order that the details thereof might be clearly understood. It is clear, however, that all these details are not essential and that the mechanical construction may be widely varied without departing 110 from the essential inventive ideas which will be defined in the annexed claims.

Claims:—

1. Door latch mechanism including a cam for operating the bolt from one side of the door, a dog therefor adapted to be protracted in a direction substantially parallel to the axis of the cam into the path thereof, means for operating the bolt from the other side of the door and a member moving therewith and adapted to ride over the end of the dog in its protracted position to return the same therefrom. 115
2. Door latch mechanism comprising a bar, the movement of which controls the bolt, a cam adapted when turned in either direction to move the bar to release the bolt, said cam having opposed shoulders, a dog 120 adapted to be shifted into engagement with 125
- 130

said shoulders to lock the cam against movement in either direction, a handle for moving the bar independently of the cam and means set in action thereby for moving said dog out of engagement with said shoulders.

3. Door latch mechanism comprising a handle-controlled cam having a recess, an element shiftable in a direction substantially parallel with the axis of said cam to engage the walls of the recess to restrain rotation of the cam in either direction and a member operated by a handle of the latch mechanism for wiping said element out from the recess.

4. Door latch mechanism comprising a casing embodying spaced plates, a cam for 15 operating the bolt turning between the plates, a button having an end extending through one of the plates and depressible to project into the path of the cam, a second mechanism for operating the bolt and a part 20 moving therewith and adapted to engage the projected end and move it outwardly.

In testimony whereof, I have signed my name to this specification.

HERMENEGILDE CARRIER.
